(57) **CLAIM**

The ornamental design for packaging with torn away perforations, as shown and described.

DESCRIPTION

FIG. 1 is a front perspective view of packaging with torn away perforations showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The segmented lines on the upper edges of left side panel, the right side panel, the rear panel and the front panel represent torn away perforations and form part of the claimed design. The segmented lines on the right edge of the left panel and the left edge of the right panel represent torn away perforations and form part of the claimed design.

The vertical and horizontal shade lines are used to show that the surfaces are substantially planar and not to be interpreted as surface ornamentation.

The broken lines shown in the interior of the packaging in FIGS. 1 and 6 depict portions of the article that form no part of the claimed design.
